GAME BOARD

Melvin John Senz, Port Angeles, Wash.

Application July 7, 1939, Serial No. 283,148

3 Claims. (Cl. 273—131)

My invention relates to the art of games. More particularly, it relates to a game whereby checkers, men, or counters, which may be of any desired character, including marbles or the like, are moved along designated paths to designated stations located at the inner and outer points of coaxially and symmetrically positioned stars in order to occupy certain stations which give the privilege of removing one of the counters of opponent.

A primary object of my invention is to provide a game which will be interesting and entertaining, as well as instructive in developing the perceptive powers in recognizing the relative position determined by triangle and straight line relationships of the checkers, counters or marbles used as playing members, such members hereinafter being referred to as counters.

The above mentioned general objects of my invention, together with others inherent in the same, are attained by the device illustrated in the following drawing, the same being preferred exemplary forms of embodiment of my invention, throughout which drawing like reference numerals indicate like parts:

Figure 1 represents a preferred form in plan view of the device embodying my invention;

Fig. 2 represents a modified form in plan view of said invention.

Fig. 3 is a view in cross section of a station having the opening extending through the board, as a marble receiving means; and

Fig. 4 is a view of a modified form of station showing a recess in the board, as a marble receiving means.

In general I provide groups of substantially coaxially and symmetrically disposed stars, the outer angle points of each star being connected to form a plurality of triangles, each triangle extending about two adjacent outer angle points of a star and the intermediate inner point thereof. All of the inner and outer angle points of each star, such as 1, 2 and 3, form stations which may be a designation on a flat surface, or when the counter is in the form of marble, the station may be a hole in the board, as in Fig. 3 or in a recess as in Fig. 4. For purposes of illustration, the stations of the innermost star are numbered 1 to 12, inclusive; the stations of the intermediate star have their stations numbered 13 to 24, inclusive; and the stations of the outermost star have their stations numbered 25 to 36, inclusive. Those stations at the inner angle points of each of the stars, such as 2, 4, 6, 8, 10 and 12 of the innermost star, are called inner

point stations and those stations at the outer angle points of each of the stars are called outer point stations, such as 1, 3, 5, 7, 9 and 11 of the innermost star. Each of the corresponding inner angle points of the respective stars is connected by lines to provide line playing paths on radial lines, for example, playing paths between stations 26, 14 and 2. Lines or playing paths follow the sides of the stars, as playing paths 37 and 38 which follow sides of the innermost star and join the inner point station 2 to the outer point stations 1 and 3 respectively. This will exemplify the playing paths joining the other points of the stars. Playing path 39 joins outer point stations 1 and 3, while playing path 40 joins outer point station 3 to outer point station 5 and so on with respect to the outer point stations of each star to form a polygon, i. e., in this instance a polygon about the innermost star. Playing path 41 joins inner point station 4 to inner point station 16 of the intermediate star and playing path 42 joins inner point station 16 to inner point station 28 of the outer star. That is, inner point stations 4, 16 and 28 are on the same radial line and are joined by said playing paths, and so on with respect to the other inner point stations.

In playing the game there would be two sides or two players, for example, A and B. Each player will be given, for example, twelve counters. These may be in the form of checkers or marbles, each twelve men having a distinctive identification characteristic, such as color or form. All the inner and outer points of the stars, such as 1, 2 and 3, which form the stations, are preferably provided with recesses in the face of the board in which the marble counters may be held.

The object of the game is to eliminate the counters of opponent from the board. For purposes of illustrating the game it will be assumed that A's counters are of a light color, whereas B's counters are of a dark color. A and B may draw or flip a coin in order to determine which is to start first, and then alternately as the turns arrive A and B place their counters at the stations which each deems most strategic until all twelve counters have been placed.

The rules of the game may be:

Rule 1.—The parties alternate in placing the counters.

Rule 2.—A player getting three of his counters in each of the angle points of a triangle, which is formed about two adjacent outer angle points of a star and the intermediate angle point thereof, or getting three of his counters in a radial playing path, disposed between inner angle points

of the stars, has the privilege of removing one of the counters of his opponent.

Rule 3.—In removing the counters, such right does not include the right to remove a counter of the opponent, which, with other counters of the opponent is in a position forming a completed triangle or line relationship, but all other counters are subject to being removed.

Rule 4.—After the counters are placed they can be moved from station to station on designated playing paths and not past a station for that particular move.

Rule 5.—Counters can be moved back and forth, and if such player forms a triangle relationship or forms three in said radial row relationship, then it counts anew, giving the right to remove one of his opponent's counters.

Rule 6.—A player may succeed in getting his counters to occupy stations where he can move from one triangle to another and thereby establish the formation of a triangle, i. e., have his counters occupy the three stations of a given triangle and thereby he will gain the privilege of removing one of his opponent's counters. This gaining control of two triangles, whereby the moving of one counter can function to count each time it is moved from one triangle to another, is termed in the game "the double triangle" or "double killer." This likewise applies to said three in a radial row.

Rule 7.—The winner is the player who succeeds in removing all of his opponent's counters.

Rule 8.—This rule is optional. When a player is reduced to three counters, thereafter he may move, on a given turn, one of his counters from any station to any other station, irrespective of whether there are playing paths joining the same or not.

Illustrating Rules 2 and 3.—If A has counters located in stations 1 and 2 and then gets a counter in station 3, he then has the right to remove one of the counters of B which does not form part of a completed triangle or straight line relationship. Also if A occupies inner point station 2 and inner point station 14, and then occupies with one of his counters inner point station 26, he has three counters in line relationship, and this likewise gives him the privilege of removing one of the counters of B, which does form a part of a completed triangle or straight line relationship.

Illustrating Rule 5.—We will assume that A has counters occupying stations 2 and 3 and stations 11 and 12. A may then move his counter on 12 into station 1 and thereby establish the relationship of a triangle between stations 1, 2 and 3 and thereby obtain the right to remove one of the counters of B. Upon his next move he may move the counter from station 1 to station 12 and be in a position upon his next move thereafter to move the counter from station 12 back to station 1 and thus reestablishing a triangular relationship and again have the privilege of removing one of the counters of B. The same applies to having three counters in a row on the inner point stations as 2, 14 and 26, and any one counter may be moved out of the row and then back to reestablish the three in a row relationship.

Illustrating rule 6.—Assuming that A has counters occupying stations 1, 2 and 3 and also counters occupying stations 9 and 10, he is in a position for moving his counters from station 1 to station 11, thereby establishing a triangular relationship between stations 9, 10 and 11, which

gives the privilege of removing one of his opponent's counters. Upon his next move he may move the counter from station 11 to station 1 and thereby reestablish a triangular relationship of stations 1, 2 and 3 and again have the privilege of removing one of the counters of B. On the next move he may move his counter from station 1 to station 11 and thus on each move reestablish a triangular relationship which gives the privilege of removing one of the counters of B. Or he may combine a triangular relationship with the three in a row relationship. For example, he may have counters occupying stations 15, 16 and 17 and stations 2 and 26. He may now move his counter in station 15 to station 14 and thereby establish three in a row, viz., counters in stations 2, 14 and 26 which would give the privilege of removing one of the counters of B. On his next move he may move the counter from station 14 back to station 15 and thereby reestablish the relationship of the triangle between stations 15, 16 and 17, which gives the privilege of removing one of the counters of B. On his next move he may move from station 15 back to station 14 and thereby make each move of the counter create the privilege of removing one of the counters of B. This is called "the double triangle" or "double killer" relationship.

It will be understood that besides having counters to occupy these particular stations mentioned above, it will be necessary for A to have so disposed his counters as to occupy stations which will protect the stations forming the triangles which he is employing to form the triangular relationship, as well as the three inner point stations employed in forming the three in a row. Otherwise B will promptly move one of his counters into position to break up the relationship of the stations which provides for removing one of the counters of B.

The operation of the game will be illustrated by assuming that A and B are the players, and by setting forth the steps of the game played on the game board, move by move. It will be assumed that B wins the draw for first play and selects station 20 as the one on which he places one of his counters. In selecting 20 B was motivated in taking a station which had four paths in which to move, rather than one which had only three ways to travel, such as station 8.

It now being A's turn, he places his first counter on station 22.

B places his second counter on station 29.

A places his next counter on station 18.

B places his next counter on station 16.

A places his next counter on station 5.

B places his next counter on station 28.

A places his next counter on station 4, thereby blocking B from gaining the relationship of three in a straight row on the radial paths joining inner point stations 4, 16 and 28.

B places his next counter on station 27, thereby establishing a triangular relationship of his counters in stations 27, 28 and 29. Having established this relationship, B gains the privilege of removing one of his opponent's (A's) counters. It will be noted that A could not prevent B in this regard because B had so arranged his counters as to develop two possibilities, either the forming of three in a row in stations 4, 16 and 28, or three in a triangle relationship in stations 27, 28 and 29. B removes A's counter on station 5.

A on his next move places anew his counter on station 5.

B then places his next counter on station 3 and thereby prevents A from establishing a triangular relationship of counters in stations 3, 4, and 5.

A then places his next counter on station 6. Thus A in turn has created two possibilities. On his next move he may establish triangular relationship with his counters between stations 5, 6, and 7 or in a radial line in stations 6, 18 and 30.

B on his next move places his counters on station 7, thereby blocking A from establishing a triangular relationship with his counters in stations 5, 6 and 7.

A on his next move places his counter in station 30, thereby establishing three in a radial row in inner point stations 6, 18 and 30. This gives A the privilege of removing one of B's counters. Accordingly, he removes B's counter in station 7.

B, upon his next turn, places anew a counter in station 7.

A, upon his turn, places his next counter in station 8.

B on his turn places his next counter in station 24.

A on his next move places a counter on station 32.

B places his next counter on station 35.

A places his next counter on station 33.

B on his next move places his counter on station 31, thereby blocking A from establishing a triangular relationship of his counters in stations 31, 32 and 33.

A on his next move places his next counter on station 21.

B places his last or twelfth counter in station 23.

A places his last or twelfth counter on station 25.

From here on the players move their counters already placed.

It being B's next move, B moves from 35 to 36, having as his objective the establishing of three in a radial line in stations 36, 24 and 12.

A moves from 18 to 19, thereby opening his three in a row in stations 6, 18 and 30.

B then moves from 16 to 17.

A moves back from station 19 to 18 and thereby reestablishing or again forming three in a radial row in inner point stations 6, 18 and 30, thereby gaining the privilege of removing one of B's counters. A elects to take B's counter on station 17. His motive in removing this particular counter was to remove the threat of B moving up into station 18 and thereby destroying the possibility of A moving from 19 back to 18 and reestablishing his three in a radial row.

B moves from station 28 to station 16.

A moves from station 18 to 19, thereby again opening up his three in a row in stations 6, 18 and 30. In making this move A overlooked the fact that B is about to move from station 16 to 28, which would give him the privilege of removing any of A's counters which are not already in a three in a row relationship or in a triangular relationship.

B moves from station 16 to 28, thereby reestablishing the triangular relationship of 27, 28 and 29 which grants him the privilege of removing one of A's counters and B elects to take A's counter in station 30.

A moves from station 8 to 9 with the idea of establishing three in a radial line in stations 10, 22 and 34. It will be noted that A at this point has a counter on stations 9, 21 and 33, but this three in a row does not count as these stations are not connected by playing paths or lines.

B moves from station 24 to 12 with the object in mind of establishing three in a row in stations 36, 24 and 12.

A moves from station 9 to 10.

B moves from station 23 to 24, thereby establishing the relationship of three of his counters in a row on apex stations on radial line or playing path joining inner point stations 36, 24 and 12, giving him the privilege of removing one of A's counters and B takes A's counter on station 22, thereby breaking up the intended combination of A forming three in a row on inner point stations 10, 22 and 34, as A could establish such relationship by moving his counter on station 33 to 34.

A now moves from station 21 to 22, thus attempting to again put another of his counters to establish the relationship of three in a row in inner point stations 10, 22 and 34.

B moves from station 29 to 30.

A moves from station 33 to 34, thereby establishing finally the three in a row in stations 10, 22 and 34, giving him the privilege of removing one of B's counters. A elects to take B's counter in station 30.

B moves from station 24 to 23.

A moves from station 32 to 33.

B moves from station 31 to 29, thereby reestablishing the triangular relationship formed by stations 27, 28 and 29, giving him the privilege to remove one of A's counters. B takes A's counter on station 33.

A moves from station 26 to 25.

B moves from station 29 to 31, thereby reopening his triangular relationship in stations 27, 28 and 29.

A moves from station 4 to 16, with the idea of establishing a triangular relationship of counters in stations 17, 19 and 18.

B moves from 31 to 29, thereby reestablishing the triangular relationship of counters in stations 27, 28 and 29, giving him the privilege of removing one of A's counters. B elects to take A's counter on station 6, thereby hindering the establishment by A of three in a row in stations 6, 18 and 30.

A now moves from station 5 to 6.

B moves from station 29 to 30.

A moves from station 16 to 17, with the idea of forming instead of a line relationship of counters in stations 6, 18 and 30, a triangular relationship of counters in stations 17, 18 and 19.

B moves from station 23 to 24, thereby reestablishing three in a row in inner point stations 36, 24 and 12, giving him the privilege of removing one of A's counters. B elects to remove A's counter on station 6, thereby preventing A from establishing a triangular relationship on stations 17, 18 and 19.

B moves from station 24 to 13.

A moves from station 22 to 23.

B moves from station 30 to 29, thereby again reestablishing the triangular relationship of counters in stations 27, 28 and 29, giving B the privilege of removing one of A's counters. B elects to remove A's counter on station 23.

A moves from station 19 to 21.

B moves from station 13 to 24, thereby establishing the three in a row relationship in inner point stations 36, 24 and 12, giving him the right to remove one of A's counters. B elects to remove A's counter on station 10, and thereby preventing the formation by A of three in a row in stations 10, 22 and 34.

A moves from station 25 to 35.

B moves from station 24 to 13.
A moves from station 21 to 22.

B moves from station 13 to 24, thereby again establishing the three in a row relationship in stations 36, 24 and 12, giving B the right to remove one of A's counters, and accordingly removes A's counter on station 34.

At this point as A has no chance of reestablishing a triangular relationship, or a relationship of three in a row, and accordingly he loses the game, as it being needless to continue the moves.

A preferable additional rule is that whenever one of the players is reduced to three counters, that he then shall have the privilege of moving one of his counters on a given move from any station to any other station without regard to playing paths.

To illustrate the playing of the game with this rule, the game may continue as follows:

A on his next move moves his counter from station 17 to station 33.

B then moves his counter from station 28 to 16.

A then moves his counter from station 22 to station 34, thereby establishing a triangular relationship of his counters in stations 33, 34 and 35, giving him the privilege of removing one of B's counters. A elects to remove B's counter on station 16.

B then moves from station 12 to station 1.

A then moves from station 35 to station 12.

B then moves from station 27 to 26.

A then moves from station 12 to 35, thereby reestablishing his triangular relationship in stations 33, 34 and 35, giving A the right to remove one of B's counters. A removes B's counter on station 24.

B then moves from station 7 to station 5.

A moves from station 34 to 22.

B moves from station 3 to 4.

A moves from station 22 to 34, thereby reestablishing a triangular relationship in stations 33, 34 and 35, giving him the privilege of removing one of B's counters. A removes B's counter on station 1.

B then moves from station 26 to 14.

A moves from station 34 to 22.

B moves from station 14 to 2.

A moves from station 22 back to 34, thereby reestablishing a triangular relationship in stations 33, 34 and 35, thereby giving him the privilege of removing one of B's men. A removes B's counter on station 2.

B moves from station 36 to 24.

A moves from station 34 to 22.

B moves from station 24 to 12.

A moves from station 22 back to 34, thereby reestablishing the triangular relationship in stations 33, 34 and 35 and giving him the privilege of removing one of B's counters and he removes B's counter on station 4.

B then moves from station 29 to 28.

A moves from station 34 to 22.

B moves from station 28 to 16.

A moves back from station 22 to 34, thereby reestablishing a triangular relationship in stations 33, 34 and 35 and thereby is given the privilege of

removing one of B's counters. A removes B's counter on station 5.

B is now down to three counters. B has the privilege of moving his counters without regard to playing paths. B moves from station 20 to 28.

A moves from 34 to 4, thereby blocking B from establishing three in a row on stations 28, 16 and 4.

B moves from station 12 to 34.

A moves from station 4 to 22.

B moves from station 34 to 4 and reestablishes his three in a row relationship on stations 16, 28 and 4, thereby giving him the privilege of removing one of A's counters. He removes A's counter on station 22 and wins the game.

Fig. 2 represents a modified form in which instead of having the inner point stations of the stars connected by playing paths, the outer point stations of the stars are connected, such as 1, 13 and 25, stations 3, 15 and 27, etc., without having the inner points stations connected. This form is not deemed as desirable as the preferred form because a counter on station, as 13, would have five pathways along which to move, while a counter on station 2, 14 and 26 would only have two paths on which to move. Thus, the discrepancy is too great. In the preferable form the counters have three and four paths on which to travel, thereby making the value of the stations more uniform.

Obviously, changes may be made in the forms, dimensions and arrangement of the parts of my invention, without departing from the principle thereof, the above setting forth only preferred forms of embodiment.

I claim:

1. A game board comprising a plurality of concentrically and symmetrically disposed stars; playing paths coincident with the sides of said stars; playing paths forming a polygon about each star and connecting between the outer angle points of such star; radially extending playing paths connecting between corresponding angle points of the stars; and counter receiving means disposed at the inner and outer points of each star.

2. A game board comprising a plurality of concentrically and symmetrically disposed stars; playing paths coincident with the sides of said stars; playing paths forming a polygon about each star and connecting between the outer angle points of such star; radially extending playing paths connecting between the inner angle points of the stars; and counter receiving means disposed at the inner and outer points of each star.

3. A game board comprising three concentrically and symmetrically disposed stars; playing paths coincident with the sides of said stars; playing paths forming a polygon about each star and connecting between the outer angle points of such star; radially extending playing paths connecting between the inner angle points of the stars; and counter receiving means disposed at the inner and outer points of each star.
